UNITED STATES PATENT OFFICE.

IRA DIMOCK, OF BOSTON, ASSIGNOR TO THE NONOTUCK SILK COMPANY, OF NORTHAMPTON, MASSACHUSETTS.

IMPROVEMENT IN QUILLS FOR SILK.

Specification forming part of Letters Patent No. 117,612, dated August 1, 1871.

To all whom it may concern:

Be it known that I, IRA DIMOCK, of the city of Boston, in the county of Suffolk and State of Massachusetts, have invented a new and useful Improvement in Silk-Quills; and I do hereby declare that the following is a full, clear, and exact description, reference being had to the accompanying drawing forming part of this specification, and in which—

Figure 1 represents a longitudinal view of a quill with silk wound upon it and displayed and secured in accordance with my improvement, and Figs. 2 and 3 are opposite end views of the same. Fig. 4 is a longitudinal view of a like quill with the outer end portion of the silk differently passed from end to end of the quill.

Similar letters of reference indicate corresponding parts.

My invention relates to the displaying and securing of silk or other thread on paper tubes, commonly called quills; and consists in a construction of the quills with slits across their opposite ends, whereby, after the silk has been wound upon the quill, the outer or loose end of the silk is passed crosswise through the slits at the one end of the quill, and then run or passed on the outside of the wound portion of the silk to the opposite end of the quill, where it is secured by passing the extreme portion of the loose end of the silk in a crosswise direction through the slits at such opposite end of the quill. By thus arranging and securing the loose end of the silk not only is said loose end or portion firmly secured in a twofold manner at opposite ends of the quill, but the body or wound portion of the silk is restrained at both ends from working off the quill, and a better display is made of the silk, whereby to judge of its grade or quality.

Referring, in the first instance, to Figs. 1, 2, and 3 of the drawing, A represents the quill, formed with slits *a a* and *b b* across its opposite ends for a short distance only of its length. The

silk *c* is wound upon the quill in the ordinary way, and its outer or loose end portion *c'* then passed crosswise through the slits *a a* at the one end of the quill, and afterward run lengthwise over the body or wound portion *c* of the silk to the opposite end of the quill, where it is crossed through the slits *b b*, and subsequently, if necessary, run back again to enter once more through the slits *a a*, passing in the course of such double run in reverse diagonal directions from the slits *a* and *b* respectively, as represented in Fig. 1; or the loose end portion *c'* of the silk may be passed, as described, first through the slits at the one end of the quill, and then be wound once or more spirally around the closely-wound portion or body *c*, and afterward be passed through the slits at the opposite end of the quill, as represented in Fig. 4. In either case, or however the loose-end portion of the silk may be run from end to end of the quill, it is important that the same should be secured in a twofold manner by passing it through the slits at both ends of the quill, and whereby the body or closely-wound portion *c* of the silk is restrained at both ends, as it is by the heads of a spool, from slipping or working off the quill. The exposure of the loose-end portion *c'* of the silk in its passage from end to end of the quill on the body or closely-wound portion *c* facilitates the examination of the silk as to grade or quality.

What is here claimed, and desired to be secured by Letters Patent, is—

The method herein described of putting up silk or other thread by winding it on a quill and then passing its loose or outer end through slits in its opposite ends of and on opposite sides of and directly across the quill, and longitudinally over the latter, substantially as specified.

IRA DIMOCK.
